UNITED STATES PATENT OFFICE.

MANUEL FELDMAN, OF NEW YORK, N. Y.

DESIGN FOR A RUG.

Application filed May 5, 1921. Serial No. 467,217. Term of patent 3½ years.

To all whom it may concern:

Be it known that I, MANUEL FELDMAN, a citizen of the United States, residing at New York, in the county of New York and State of New York, have invented a new, original, and ornamental Design for a rug, of which the following is a specification, reference being had to the accompanying drawing, forming a part thereof.

The figure is a plan view of a rug, showing my new design.

What I claim is:

The ornamental design for a rug, as shown.
MANUEL FELDMAN.
